PROTECTIVE EYEPIECE

Willis A. Whipple and Robert L. Maleom, Chicago,
Ill., assignors to Chicago Eye Shield Company,
a corporation of Illinois

Application August 17, 1943, Serial No. 498,996

1 Claim. (Cl. 2-8)

This invention relates to protectors of the helmet or mask type used to prevent injury to the eyes, faces, and heads of welders and others by glaring light, sparks, and other particles.

More particularly, the invention pertains to the eyepieces of such protective devices that include two frames, constituting inner and outer members, slidably one within the other to assemble in the sight opening of a sheet material facepiece with the marginal area of the material adjacent to the opening clamped between the two frames. The inner frame has a rather thin wall.

It is an object of the invention to form the inner frame with members outside of its wall to receive fasteners holding the two frames together.

Another object is to form the fastener receptive members integrally with the inner member wall as strengthening elements thereof.

Further, it is an object so to form the fastener receptive members and the outer frame that those members function to guide the two frames to assembled position in the facepiece and contribute to maintenance of the frames in proper relation to each other.

When considered with the description herein, characteristics of the invention are apparent in the accompanying drawings, forming part hereof, wherein an adaptation of the invention is disclosed for purpose of explanation.

Like reference-characters refer to corresponding parts in the views of the drawings, of which—

- Fig. 1 is a front view;
- Fig. 2 is a front view of the inner frame;
- Fig. 3 is an end view of that frame;
- Fig. 4 is a section on line 4—4, Fig. 2;
- Fig. 5 is a front view of the outer member;
- Fig. 6 is a rear view of that member;
- Fig. 7 is a section on line 7—7, Fig. 1;
- Fig. 8 is a section on line 8—8, Fig. 5.

The eyepiece of the invention is for closure of the sight opening in the arcuate front of a facepiece to prevent injury to the eyes of the user. The facepiece may be of sheet material of any suitable kind. It is conventional to make it of tough and substantially rigid fiber material pressed to shape. The facepiece material is designated in the drawings by the numeral 8.

Frames of the eyepiece may be made of metal or other suitable material. Currently it is common practice to make them of strong and comparatively light moldable material, and as ex-

emplified in the drawings it is of such material and of rectangular shape.

An inner member 9 of the eyepiece includes a flange 10 extending laterally and outwardly from end walls 11 and upper and lower walls 12. The flange is arcuate to conform to the curvature and to abut closely against the inside of the facepiece. The wall part of the inner frame is of such outside shape and dimension that it fits rather closely against the edge of the facepiece sight opening.

The front edge of the wall lies in a plane. Pillar-like members 13 fixed on the frame outside of the wall thereof at the ends extend almost to the edge of the wall. They may be formed on and integrally with the end walls and flange, during molding or other fabrication of the frame, and then they constitute end wall strengthening members. Flanges 14 inside of the wall at each end provide a seat for a glass retaining spring.

The inner frame is for association with an outer frame 15 that comprises end walls 16 and upper and lower walls 17. The outer or front side of the outer frame is a flat surface on which is a substantially rectangular rib 18 within which a marginal flange 19 extends inwardly of the opening inside of the walls. The end walls 16 are formed with slots 20 of a size and shape snugly to receive the members 13 of the inner frame.

The wall edge is arcuate to conform to the curvature of the inner member flange 10. The outer frame has passages 21 extending thereinto from its front, these passages being aligned with the members 13 to accommodate fasteners extending into those members.

The side and end walls of the inner frame 9 and of the outer frame 15 constitute, on each of those frames, a single encompassing wall, and that of the inner frame defines the sight opening through the eyepiece. The interior perimeter of the outer frame is of a size and shape to receive the wall of the inner frame with a close fit.

When the two frames are to be assembled in the sight opening of a facepiece, the inner frame is pushed into the opening from the inside until its flange is against the inside surface of the facepiece, the material of the facepiece having been notched at the edge of the opening to enable it to straddle the members 13. A spring 22 in the inner frame rests on the flanges 14. The outer frame is pushed over the inner frame until its wall edges are against the outer side of the facepiece. The spring 22 holds a glass 23 against the flange 19 of the outer member. This glass usually is clear. Suitable fasteners, such as screws 24, are disposed through the passages 21 of the

outer frame into the members 13 of the inner frame, they draw and maintain the two frames together, and cause them to clamp the facepiece between the flange of the inner member and the wall edge of the outer member.

During assembly, the members 13 function as guides in the slots 20 to facilitate sliding movement of the outer frame over the inner one, they permit the inner member to be formed with a thinner wall than would be required to receive such fasteners as screws, and they constitute strengthening elements for the end walls.

An eyepiece of this kind is fitted with a colored glass to protect a workman from glare of intense light such as encountered in welding, the glass being mounted so that it may be swung out of the line of sight when clear vision is desired. Such a colored glass 25 may be carried in a frame 26 having a part 27 through which extends a pivot-pin 28 carried by ears 29 on the outer frame 15. When the frame 26 is closed, its inner marginal surface contacts the surface of the outer frame, and it has a groove 30 to receive the rib 18, so that light is prevented from entering back of the colored glass.

We claim:

An eyepiece, for association with a protective facepiece of sheet material at its sight opening, comprising an inner frame including a wall, defining a sight opening, to extend from the inside through the facepiece sight opening, a flange extending laterally and outwardly from said wall to abut the inside of the facepiece, and pillar-like members on the outside of and protruding from said wall and extending toward the front of said frame, an outer frame, adapted to have associated with it means to carry a protective transparent member, said outer frame comprising a wall encompassing the wall of said inner frame and having slots in which said pillar-like members are disposed and said outer frame having a back edge to clamp the facepiece against the flange of said inner frame, and fasteners extending from the front of said outer frame into said pillar-like members maintaining the two frames together.

WILLIS A. WHIPPLE.
